United States Patent Office

Des. 208,315

Patented Aug. 15, 1967

208,315

GAME FIGURE

Perry J. Grant, Pacific Palisades, Calif., assignor to The Toy Development Center, Inc., a corporation of California

Filed Mar. 3, 1966, Ser. No. 1,272

Term of patent 14 years

(Cl. D34—15)

FIG. 1.

FIG. 2.

FIG. 3.

FIG. 5.

I claim:

The ornamental design for a game figure, substantially as shown.
